NOVELTY DISPLAY COVER AND CONTAINER

Albert A. Webb, Westmount, Quebec, Canada,
assignor to Imperial Tobacco Company of
Canada, Limited, Montreal, Quebec, Canada

Application December 16, 1931
Serial No. 581,477

6 Claims. (Cl. 206—44)

This invention relates to display containers for cigarettes, tobacco and other commodities and particularly to a display container of the kind disclosed in Canadian Patent No. 217,188, 5 granted March 21, 1922.

The container disclosed in said patent is characterized by the provision of a removable cover including retaining and display card portions joined together along a fold line 10 permitting the display card portion to be arranged in a horizontal position covering the container contents or in an inclined or substantially upright display position. In this construction the retaining portion is arranged in 15 upright position against one of the vertical walls of the container body and is held against displacement solely by engagement with the container contents. Consequently when the container is emptied of its contents there is a 20 tendency for the retaining portion to become displaced by the weight of the display card portion when the latter is in its display position. The present invention overcomes this objection by providing an interlocking connection 25 between the cover and the container body, which is effective to securely hold the cover in its display position irrespective of whether the container is filled or is emptied of its contents. A further feature of the present invention consists also in the provision of an improved form 30 of container body especially adapted for interlocking engagement with the cover.

Proceeding now to a more detailed discussion of the invention reference will be had to the 35 accompanying drawings, wherein—

Fig. 1 is a plan view of a special form of blank from which the container body forming part of this invention is adapted to be formed.

Fig. 2 is a longitudinal sectional view through 40 a partly erected container formed from the blank shown in Fig. 1. This view also shows a cover in vertical section assembled with the container.

Fig. 3 is a perspective view of a complete container and cover assembly.

Fig. 4 is a transverse sectional view taken along the line 4—4 of Fig. 3.

Fig. 5 is a plan view of a display cover blank provided in accordance with this invention.

Fig. 6 is a view similar to Fig. 5 showing a slight modification.

Fig. 7 is a perspective view of a complete container and display cover assembled with the cover arranged to overlie the container contents.

55 Referring more particularly to the drawings,

the body portion of the container is preferably formed from a blank of the type shown in Figure 1. This blank is provided with score lines 11 defining a bottom wall 12 lying between the side wall sections 13. Each section 13 is joined 60 along the fold line 14 to a supplementary side wall section 15, the latter being provided with a flap extension 16 joined thereto along the fold line 17. A pair of end walls 18 are formed integral with the bottom wall 12 along the 65 fold lines 19, each end wall being provided with a pair of laterally extending locking flaps 20 joining said wall along the fold lines 21. The outer portion of each flap 20 is reduced in width and partially separated from the body of the 70 flap by a slit 22 to form a locking tongue 23, said tongue joining the body of the flap along a fold line 24 coinciding with the slit 22. The companion locking tongues 20 of each end wall 18 are reversely arranged as shown and adapted to 75 interlock with the corresponding tongues of the remaining end wall. At points near the fold lines 11 the bottom wall 12 is also provided with locking tongues struck from the material of said wall, as indicated at 12a.

The folding of the blank into box formation is illustrated to advantage in Figures 2 to 4 inclusive. The end walls 18 are bent along the fold lines 19 to extend upwardly from the bottom wall 12. The locking flaps 20 of each end wall are bent inwardly along the fold lines 21 and arranged with the tongues 23 of one pair of flaps disposed in interlocking relation with the tongues 23 of the remaining pair, as shown to advantage in Figure 2. The side wall sections 13 are then folded upwardly along the fold lines 11 to lie outwardly of the adjacent flaps 20, the supplementary side wall sections 15 being folded downwardly along the fold line 14 to lie against the inner sides of said flaps. The 95 flap extension 16 of the side wall sections 15 are then engaged beneath the locking tongues 12a of the bottom wall 12, as shown to advantage in Figure 3.

The display cover which forms the principal 100 feature of this invention is preferably made from the blank shown in Figure 5. It comprises a display card 26 and a retaining portion 27 integrally joined together along the fold line 28. The lower corners of the display card 26 are 105 separated from the retaining portion 27 by horizontal slits 29 coinciding with the fold line 28. The inner ends of the slits 29 are extended upwardly a short distance to form vertical slits 30 thereby providing locking tongues 31 joined 110

to the body portion of the display card along the fold line 32. The sides of the retaining portion are extended beyond the display card in the form of laterally projecting flaps 33 foldable along the score line 34. The display cover is adapted to be selectively arranged in the body portion of the container to assume a substantially upright display position as shown in Figs. 2 to 4 inclusive or to assume a horizontal position overlying the container contents as shown in Figure 7. On referring to the first mentioned figures, it will be noted that the retaining portion 27 is arranged against the inner surface of one of the end walls 18 with the flaps 33 of said retaining portion inserted between the side wall sections 15 and the adjacent end wall locking flaps 20. In this position of the display cover the locking tongues 31 are bent outwardly along the fold lines 32 and engaged with the outer surface of the end wall 18 to hold the display card 26 in the upright position shown, the inner or both the inner and outer surfaces of the display card 26 having suitable advertising matter printed or otherwise arranged thereon. When the display card is to be disposed in a horizontal position to overlie the container contents, this is accomplished by raising the retaining portion 27 until the lower edges of the tongues 31 clear the upper edge of the end wall 18. The display card 26 is then folded inwardly along the fold line 28 to assume the horizontal position shown in Figure 7. In this connection it will be noted that the upper edges of the flaps 33 terminate a sufficient distance below the upper edges of the side wall sections 13 to permit the upward movement of the retaining portion 27 necessary to disengage the locking flaps 31 with the end wall 18.

The display cover shown in Figure 6 is substantially the same as that shown in Figure 5 except that the side flaps 33 of the retaining portion 27 are omitted. These side flaps are not absolutely necessary since the engagement of the locking tongues 31 with the end wall 18 of the container body provides an interlocking connection which is ordinarily sufficient to retain the display card 26 in the position shown in Figs. 2 to 4 inclusive. The interlocking connection provided between the display cover and the container body by reason of the tongues 31 and the flaps 33 or by reason of the tongues 31 alone is of advantage in that it serves to effectively retain the display cover in the position shown in Figs. 2 to 4 inclusive after the container has been completely emptied of its contents. Without this interlocking connection there is a tendency for the display cover to become displaced unless supported in position by engagement with a portion of the container contents.

Having thus fully described what I now conceive to be the preferred embodiment of my invention, it will be understood that various modifications may be resorted to within the scope and spirit of the appended claims.

Having thus described my invention, what I claim is:

1. A display cover adapted to be removably associated with an open top container to serve either as a cover or as a display card therefor, said cover comprising a single sheet of material presenting a display card portion and a retaining portion integrally joined together along a suitable fold line, the lower corners of the display card portion being separated from the retaining portion by slots affording locking tongues con-

nected to the body of the display card portion along fold lines spaced from but paralleling the first mentioned fold line.

2. A display cover as claimed in claim 1 in which the sides of the retaining portion are extended beyond the display card portion in the form of laterally projecting flaps joining the retaining portion along suitable lines of fold. 80

3. A display cover adapted to be removably associated with an open top container to serve either as a cover or as a display card therefor, said cover comprising a single sheet of material presenting a display card portion and a retaining portion having its upper edge joining the lower edge of the display card portion along a suitable line of fold, the lower corner of the display card portion being separated from the retaining portion by slits affording locking tongues connected to the body of the display card portion along fold lines spaced from but paralleling the first mentioned fold lines, the sides of said retaining portion being extended beyond the display card portion in the form of laterally projecting flaps joining the retaining portion along suitable fold lines and having their upper edges 90 lying in a plane below the plane of the fold line along which the display card and retaining portions are joined together. 95

4. In combination, a container body comprising bottom, side and end walls, said side walls 105 presenting inner and outer sections joined together at their upper edges, a display cover comprising a retaining portion adapted to be arranged in upright position against the inner surface of one of said end walls and a display 110 card portion having its lower edge integrally joined to the upper edge of the retaining portion along a suitable fold line so that said display card portion may be disposed in a horizontal position over the top of the container or in an inclined or substantially upright display position, the lower corners of the display card portion being separated from the retaining portion by slits affording locking tongues connected to the body of the display card portion along fold lines 120 spaced from but paralleling the first mentioned fold line, said tongues being engageable with the outer surface of the end wall engaged by the retaining portion so as to hold the display card portion in its display position and projecting 125 flaps carried by the sides of the retaining portion fitted between the inner and outer sections of the side walls of the container, said flaps being of a height less than the height of said side wall sections so that the retaining card portion is 130 capable of limited vertical movement sufficient to permit the locking tongues of the display card portion to be engaged with the end wall against which the retaining portion bears to hold the display card portion in its display position or to be disengaged with said end wall to permit the display card portion to be folded to a horizontal position over the top of the container. 135

5. A display cover formed from a single sheet 140 of material presenting a display card portion and a retaining portion joined together along a suitable line of fold, the lower corners of the display card portion being separated from the retaining portion by slits extending inwardly from opposite 145 edges of the sheet along the said line of fold and having their inner ends extended at right angles to said line of fold and into the body of the display card portion to provide locking tongues connected to the body of said display card por- 150

tion along fold lines spaced from but parallel-
ing the first mentioned fold line.

6. A display cover adapted to be removably
associated with an open-top container to serve
5 either as a cover or as a display card therefor,
said cover comprising a display card portion
and a retaining portion integrally joined to-
gether along a suitable fold line, and a tongue

struck from the display card portion so that the
free end of the tongue is directed towards said
fold line, said tongue being connected to the
body of the display card portion along a fold
line adjacent and parallel to the first mentioned
fold line. 80
